Primary Examiner — Joseph Kukella*Assistant Examiner* — Arva P Adams(57) CLAIM

The ornamental design for a French press coffee maker, as shown and described.

DESCRIPTION

FIG. 1 is a top-right perspective view of a French press coffee maker, showing my new design;
 FIG. 2 is a bottom-right perspective view thereof;

FIG. 3 is a front elevational view thereof;

FIG. 4 is a rear elevational view thereof;

FIG. 5 is a bottom plan view thereof;

FIG. 6 is a top plan view thereof;

FIG. 7 is a right side elevational view thereof; and,

FIG. 8 is a left side elevational view thereof.

The broken lines in the drawings depict portions of the French press coffee maker that form no part of the claimed design.

1 Claim, 8 Drawing Sheets(56)
